UNITED STATES PATENT OFFICE.

DAVID G. KNITTEL AND WILLIAM J. DAVIS, OF PITTSBURGH, PENNSYLVANIA,
ASSIGNORS TO AMERICAN FIRE ALARM COMPANY, OF PITTSBURGH, PENNSYLVANIA, A CORPORATION OF DELAWARE.

SIGNAL-TRANSMITTER.

1,092,919.

Specification of Letters Patent. Patented Apr. 14, 1914.

Application filed March 19, 1913. Serial No. 755,483.

To all whom it may concern:

Be it known that we, DAVID G. KNITTEL and WILLIAM J. DAVIS, residing at Pittsburgh, in the county of Allegheny and State of Pennsylvania, both citizens of the United States, have invented or discovered certain new and useful Improvements in Signal-Transmitters, of which improvements the following is a specification.

10 Our invention has to do with the construction and operation of signal stations, such as police reporting boxes, wherein suitable mechanism is provided to transmit variable codes from the box to a central station.

15 One object of our invention is to improve the general construction of the code-transmitting mechanism contained within such boxes, to the end that its operation may be certain and positive at all times.

20 In the accompanying drawing, which forms part of our specification, we have illustrated an embodiment of our invention.

Figure 1 of the drawing is a side view of a code transmitter and a portion of the 25 reporting box within which such transmitter is placed, the casing for such transmitter being shown in section; Fig. 2 is a sectional view taken on the line II-II, Fig. 1; and Figs. 3 and 4 are detail views which will be 30 referred to more particularly hereafter.

Like numerals are used to designate like parts.

The general arrangement of the transmitter shown herein is such that the proper setting of an indicator or finger and the pulling of a lever will set in motion instrumentalities whereby an electrical circuit will be interrupted a predetermined number of times, each of such interruptions being effective to operate a recording instrument or ring a bell at the central station. The signals usually transmitted by such mechanisms, and which the particular construction shown herein is adapted to transmit, is the 45 number of the box or reporting station, and a special signal, varying according to the circumstances of the call, and predetermined by the positioning of the above mentioned indicator. The mechanism or transmitter for thus interrupting the electrical circuit comprises a rotatable box-number wheel 1, a special signal wheel 9, an arm 15 carrying a circuit closing pen 16 and adapted

to be moved by either of said wheels, and a shunted electrical circuit. Referring first to 55 the several said elements of the transmitter in the order named, and subsequently to the circuit which it controls, the box-number wheel 1 is a tooth-provided disk secured to a shaft 2, which, by means of a suitable 60 clock work mechanism 3, is adapted to be revolved one complete revolution upon each operation of the transmitter, said mechanism 3 being placed in motion by turning, through a limited arc, a lever 4 secured to a 65 shaft 5. The detail construction of the clock work 3, being well understood by those skilled in the art, need not be here described. The periphery of the wheel 1 is provided with an extended projection 6 and with a 70 series of teeth 7 corresponding in number and arrangement to the box number of the particular reporting box in which the transmitter is placed; also, the shaft 2 has a segmental pinion 8 secured to it, and in circumferential arrangement upon said shaft this pinion extends between the end of the projection 6 and the first of the series of teeth 7.

The special signal wheel 9 is secured to a rotatably mounted shaft 10, and is provided upon its periphery with a series of evenly spaced teeth 11. Secured to the same shaft there is also a segmental pinion 12 adapted to be engaged by the pinion 8 of shaft 2, and a tooth-provided insulation 85 block 13 adapted to control a shunt circuit, as will appear more fully hereafter. The position of the special signal wheel, in advance of the transmission of a given signal, varies according to the special signal desired to have transmitted, such signals consisting simply in the different number of interruptions of the electrical circuit. In order to set the wheel for a predetermined signal an indicator or finger 30 is rigidly 90 secured to the shaft 10, and a suitably graduated dial (not shown herein) is placed below such finger.

The arm 15, which carries the circuit controlling pen 16, is pivoted at 17 and bears, 100 through suitable rollers 18 and 19, upon the wheels 1 and 9. As will be readily seen, this arm, which is rigid throughout, is pivoted at one end and bears upon said wheels at points between the contact pen 16 and its 105 pivot point 17. The advantage of this par-

ticular construction is that the toothed wheels, operating directly upon the arm which carries the contact pen, cannot throw such arm out of adjustment, thus causing confusion in the signals transmitted.

The electrical circuit, which is opened and closed by the movement of the contact pen 16, extends to the transmitter by electrical conductors 20 and 21, which are connected thereto by suitable binding posts 22 and 23. The binding post 22 is electrically connected successively to binding posts 24 and 25, from the latter of which a contact arm 26 projects to the contact pen 16; and the binding post 23 is similarly connected to posts 27 and 28 from which also extends a contact arm 29. This main electrical circuit is adapted to be shunted or short circuited by two independent means. In the first place it is desirable to have a path of electrical continuity, other than through arms 26 and 29 and pen 16, when the transmitter is inoperative, for the reason that foreign currents are liable to burn out such arms which are necessarily delicate. To such an end a contact arm 31 and a spring-arm contact member 32 are secured, respectively, to binding posts 22 and 23, and an abutment 33 is secured to the shaft 5, the arrangement being such that, when the transmitter is inoperative or at rest, said abutment will be effective to hold the spring arm 32 yieldingly in contact with the arm 31; but, when the operating lever 4 is turned to set in motion the transmitting mechanism (as heretofore explained), said abutment 33 moves away from the spring-arm 32 and allows it to break contact with the arm 31, as shown in Fig. 3. As will be readily understood, the abutment 33, after the transmitter has been set in motion, gradually returns to its circuit closing position. The spring 36, carried by the abutment 33, engages the wheel 9 and holds it yieldingly in its pre-arranged position until the transmitter is set in motion. The second of said shunt circuits is provided in order to prevent, when desired, the extended wheel projection 6 causing a long warning ring in the central station in advance of the special signal and box number. This shunt or short circuit is effected by means of a contact arm 34 and spring-arm contact member 35 secured, respectively, to binding posts 24 and 27, the above mentioned insulation block 13 being adapted, when the index finger 30 is properly set, to bear upon said spring-arm 35 and press it into contact with the contact arm 34. The position of said block 13 upon the shaft 10 with relation to the wheel 9 is clearly shown in Fig. 4.

The complete operation of the transmitter for all signals may be clearly understood from descriptions of two of the possible signals. The several parts of the transmitter

are shown in normal inoperative position in Fig. 2 of the drawings, and in this position it will be seen that the abutment 33 is effective to close the circuit through contact arm 31 and spring arm 32, and that the movement of the pen 16, caused by the setting of the special signal wheel 9, will therefore not effect an intermittent breaking of the circuit.

The simplest signal, which in the particular arrangement of the present disclosure may be sent, is the box number preceded by the long warning alarm. To transmit the signal the indicator 30 is not moved. A turning of the lever 4 through its permissible range of movement will be effective to move the abutment 33 and the spring 36 to the position indicated in Fig. 3, wherein the circuit through the arms 31 and 32 is open. When the lever is released the wheel 1 revolves at a constant speed in a counter clock-wise direction, as indicated by the arrow placed thereon. The projection 6 raises the arm 15 and contact pen 16, thus opening the circuit and causing the long advance alarm to be transmitted. Following the long alarm the several teeth 7 intermittently raise the arm 15 and thereby transmit the box number.

When it is desired to send a special signal and to dispense with the advance long alarm, the indicator 30 is suitably adjusted, and by such adjustment the wheel 9, segmental pinion 12 and insulation block 13 are turned in a counter clock-wise direction. The insulation block 13, arranged on the shaft 10 below the wheel 9, is provided with teeth alternating with the teeth 11 of said wheel, the arrangement being such that, when the spring arm 35 rests upon the point of a tooth of such block and thereby holds the arm 35 in contact with the arm 34, the roller 19 of arm 15 will lie in a depression between adjacent teeth 11 of wheel 9; and when the roller 19 is on the point of a tooth 11, the hump of arm 35 will lie between adjacent insulation block teeth. It will therefore be seen that as the wheel 9 and insulation block 13 are moved by engagement of pinion 8 with pinion 12 the circuit will be simultaneously opened and closed by the arm 35 and pen 16. After the indicator 30 has been set the lever 4 is pulled, and when released the wheel 1 moves as described above. During such time as the extended projection 6 on such wheel holds the arm 15 in raised position the circuit will be closed through arms 34 and 35, so that no advance alarm or signal will be transmitted by the projection 6. Following the passing of said projection beyond the roller 18 the pinion 8 engages pinion 12 and moves wheel 9 and block 13, which members, as described above, simultaneously break the circuit a predetermined number of times to send the desired special signal. The box

number then follows the special signal and the entire operation is completed.

We do not wish to limit ourselves to the details of construction shown herein, for obviously many changes can be made therein by those skilled in the art without departing from the spirit of our invention as defined in the claims.

We claim as our invention:

10 1. In a multiple signal transmitter, the combination of an electrical circuit, box-number and special-signal wheels, and a single pivoted arm provided with a circuit-controlling contact member, said arm bearing upon each of said wheels, the portion thereof between and including its bearing points upon said wheels being in fixed and immovable relative position.

20 2. In a multiple signal transmitter, the combination of an electrical circuit, box-number and special-signal wheels, and a single rigid arm pivoted at one end and provided at its opposite end with a circuit-controlling contact member, said arm bearing upon each of said wheels between its pivot point and said contact member and movable thereby.

30 3. In a multiple signal transmitter, the combination of a main electrical circuit, box-number and special-signal wheels, a pivoted arm provided with a circuit-controlling contact member and movable by each of said wheels, a shunt circuit closed while said transmitter is at rest but open during its period of operation, a second shunt circuit, and means for closing said second

shunt circuit during a portion of the period of operation of said transmitter.

4. In a multiple signal transmitter, the combination of a main electrical circuit, 40 box-number and special-signal wheels, a pivoted arm provided with a circuit-controlling contact member and movable by each of said wheels, a normally-open shunt circuit, and means movable with said special- 45 signal wheel for closing and opening said shunt circuit simultaneously with the closing and opening of said main circuit by said special signal wheel.

5. In a multiple signal transmitter, the 50 combination of a main electrical circuit, box-number and special-signal wheels provided on their peripheries with arm-moving teeth, a pivoted arm provided with a circuit-controlling contact member and movable 55 by said teeth on each of said wheels, a normally-open shunt circuit, and an insulation block provided on its periphery with teeth alternating with the teeth on said special-signal wheel, said block movable 60 with said special-signal wheel and effective to close and open said shunt circuit simultaneously with the closing and opening of said main circuit by said special-signal wheel. 65

In testimony whereof we have hereunto set our hands.

DAVID G. KNITTEL.
WILLIAM J. DAVIS.
